UNITED STATES PATENT OFFICE.

GEORGE H. MERWIN, OF MILFORD, CONNECTICUT.

TROLLEY-HEAD AND TROLLEY.

No. 921,265.

Specification of Letters Patent.

Patented May 11, 1909.

Application filed November 27, 1908. Serial No. 464,586.

To all whom it may concern:

Be it known that I, GEORGE H. MERWIN, a citizen of the United States, residing at Milford, county of New Haven, State of Connecticut, have invented a new and useful Trolley-Head and Trolley, of which the following is a specification.

- This invention relates to trolley heads and trolleys for electric railways.
- 10 It is one of the objects of the invention to provide a simple and relatively inexpensive self-oiling trolley head that shall be thoroughly durable and practical and will not require constant attention.
- 15 A further object of the invention is to provide a trolley having removable contact plates which may be replaced when worn at slight expense, the head and trolley being thus caused to wear for an almost unlimited 20 length of time.

With these and other objects in view I have devised the novel structure of which the following description in connection with the accompanying drawings is a specification, reference characters being used to indicate the several parts.

Figure 1 is a side elevation of my novel head and trolley as in use; Fig. 2 a plan view of the head with the operative parts of the 30 head and trolley in horizontal section; Fig. 3 a sectional view on the line 3—3 in Fig. 2; Fig. 4 an elevation of the trolley with one of the contact plates removed, the shaft being in section; Fig. 5 an elevation of a contact 35 plate removed; Fig. 6 an elevation of a side plate removed; and Fig. 7 is an elevation of the body of one of the boxes removed.

10 denotes my novel trolley head as a whole, 11 the pole and 12 the trolley. The head comprises arms 13 between which the trolley is pivoted. Each arm is provided with an oil reservoir 14 having a filling opening 15 which is closed by a screw cap 16. The trolley is carried by a shaft 17 which rotates 45 in boxes 18 secured in the head. The trolley comprises a web 19, a peripheral flange 20 having a groove 21, bearing plates 22 and side plates 23. The bearing plates are made in two semi-circular parts, as shown in Figs. 50 4 and 5, which together form the complete bearing of the trolley. The plates are substantially V-shape in cross-section and are shaped externally to fit closely in the groove of the trolley and internally to receive the 55 current wire (not shown). They are secured to the flange of the trolley by screws or

rivets 24. It is of course well understood that most of the wear upon trolleys is upon the flanges and that when the flanges of ordinary trolleys are seriously worn, new trolleys 60 must be substituted in their places. With my novel trolley it is simply necessary to remove the bearing plates and replace them with new ones, an operation which may be performed quickly and at trifling expense, 65 thus avoiding the expense of new trolleys when the flanges become worn. The shaft is provided at its mid-length with a reduced angular portion 25. The web of the trolley is provided with a central hole 26 which receives the full diameter of the shaft. The side plates are each provided with a radial slot 27 extending from the periphery slightly past the center and made angular at its inner end, which just receives the angular portion 70 25 of the shaft. The side plates are secured to the web with slots out of alinement by screws or rivets 28. These side plates lock the trolley to the shaft, as will be more fully explained.

75 The boxes in which the shaft rotates each comprise a body 29 having an external head 30, internal and external nuts 31 and a cap 32. The bodies are cylindrical in form and externally screw threaded to engage correspondingly-threaded openings 33 in the opposite walls of the arms of the head through which the body passes. The inner end of each body is engaged by a cap 32 having an opening 38 for the shaft. Between the end of the cap and one side of the arm and between the head and the opposite side of the arm are nuts 31 which serve as lock nuts. Between the ends of the body and the bases of the caps I place packing 80 indicated by 34 which prevents escape of oil. The opposite ends of the shaft are received in central longitudinal openings in the bodies which are indicated by 35. Each body is provided with a radial opening 36 85 lying within the oil reservoir and extending to the central opening, which permits oil to enter freely from the reservoir and pass to the shaft. In practice, the openings 35 in the bodies become filled with oil in which the 90 shaft runs, the packing preventing the escape of oil. One of the bodies, the lower one as shown in Fig. 2, has its central opening extending entirely through it, the outer end of the opening being closed by a screw 105 plug 37.

The mode of assembling is as follows:

The parts of the upper box, as seen in Fig. 2, are first placed in the arm but the body, cap and nut are not screwed tightly to place. The body of the lower box with the outer nut 5.31 thereon is then turned through the lower arm of the body, and then the trolley without the side plates is placed between the boxes. The inner nut is then turned on and then the cap with the packing therein is 10 then turned on the inner end of the body. The shaft is then inserted through the central opening in the lower body and the opening closed by means of the screw cap; then the side plates of the trolley are slipped to 15 place in engagement with the shaft, as shown in Figs. 2 and 5; then the side plates are secured to the trolley by screws or rivets 28, after which the outer nuts are turned tightly against the outer sides of the 20 arms; then the bodies are turned inward tightly to place; then the inner nuts are turned tightly against the inner sides of the arms and the caps are tightened up, the result being that the trolley is accurately 25 centered between the arms and is left free to rotate between the caps of the two boxes.

Having thus described my invention I claim:

1. The combination with the arms of a 30 trolley head having threaded openings, of boxes comprising bodies turned into said openings from the outer side, caps engaging the inner ends of the bodies, a shaft journaled in the boxes and a trolley carried by the 35 shaft.

2. The combination with the arms of a trolley head having threaded openings, of

boxes comprising bodies turned into said openings and having heads, caps engaging the other ends of the bodies, lock nuts between the heads and caps and the opposite sides of the arms, a shaft journaled in the boxes and a trolley carried by the shaft. 40

3. The combination with a trolley head having oil reservoirs and boxes communicating with the oil reservoirs, of a shaft journaled in the boxes and having an angular portion and a trolley comprising a web having an opening which receives the full diameter of the shaft and side plates secured to the web and having slots which receive the angular portion of a shaft and lock the trolley thereto. 45

4. The combination with a trolley head having boxes, of a shaft journaled in the 55 boxes and having a reduced angular central portion, of a trolley having a web with an opening through which the shaft may pass and side plates secured to the web and having radial slots made angular at their inner ends 60 to closely engage the angular portion of the shaft.

5. A trolley comprising a grooved flange, a web having a central opening and side plates secured to the flange and provided 65 with radial slots, substantially as described, for the purpose specified.

In testimony whereof I affix my signature, in presence of two witnesses.

GEORGE H. MERWIN.
